UNITED STATES PATENT OFFICE.

GEORGE F. NEWTON, OF KANSAS CITY, KANSAS, ASSIGNEE, BY MESNE ASSIGNMENTS,
TO UNIVERSAL FORM CLAMP COMPANY, OF CHICAGO, ILLINOIS, A CORPORATION OF
ILLINOIS.

COLLAR-ADJUSTING CLAMP.

1,275,461.

Specification of Letters Patent. Patented Aug. 13, 1918.

Application filed November 4, 1912. Serial No. 729,543.

To all whom it may concern:

Be it known that I, GEORGE F. NEWTON, a citizen of the United States, residing at Kansas City, in the county of Wyandotte and State of Kansas, have invented certain new and useful Improvements in Collar-Adjusting Clamps, of which the following is a specification.

This invention relates to collar adjusting clamps and more especially to a clamp for adjusting a collar to hold it at the desired point until the collar can be fastened at such point.

With this general object in view and others as hereinafter appear, the invention consists in certain novel and peculiar features of construction and organization as hereinafter described and claimed; and in order that it may be fully understood reference is to be had to the accompanying drawing, in which—

Figure 1, is a vertical section showing the method of adjusting and securing collars on hangers for the purpose of holding false-work in position.

Fig. 2, is a view showing a part of a concrete column and false-work and also shows in elevation, the use of the adjusting collar clamp.

30 In the said drawing, 1 is a bolt having a central bore or passage 2, and a clamping screw 3.

4 is a nut screwed upon the threaded stem of the bolt and provided with an angular external surface 5 whereby it may be readily turned with a wrench.

The bolt 1 and nut 4 constitute a tightening device adapted for longitudinal expansion and contraction and for longitudinal adjustment on the rod and for longitudinally adjusting the collar on said rod, as hereinafter appears.

In Fig. 1, 6 indicates a false-work upon which a concrete floor 7 is laid. 8 is a reinforcement beam for the floor and 9 a concrete rib depending from the floor and inclosing that portion of the beam below the floor line.

10 is the bottom portion of the false-work underlying rib 9 and 11 is one of a series of 50 ribs extending transversely of the bottom 10. 12 is a hanger suspended from the beam 8, and extending downward through the bottom 10 and cleat 11.

13 are collars secured on the arms of the

hanger and forming supports for the overlying portion of the false-work, the collars being secured rigidly to the rods by screws 14.

Preferably the collars 13 are first fitted on the arms of the hanger and the set screws 14 are turned so as to bear with sufficient force on the arms to support the weight of the overlying portion of the false work before the concrete floor is laid. The clamping device is then slipped upon one of the arms of the hanger until the nut 4 engages the underside of the collar on such arm and then the clamping screw 3 is turned to secure the bolt 1 rigidly on the arm. Set screw 14 of the overlying collar is then loosened and a wrench is employed to screw the nut 4 upwardly and thus slide the overlying collar upward until the false work has attained the desired position, it being noted that by the means described sufficient force can be brought to bear on the cleat 11 to flatten out the bottom 10 in the event that the same is slightly twisted by warpage or otherwise. After the bottom 10 is raised to the point desired, the set screw 14 is turned to secure the collar 13 reliably in place. Set screw 3 is then loosened to permit the clamping device to be slipped on the other arm of the hanger and then the same adjusting operation of the collar on said arm is effected, after which the clamping devices are removed from the rod.

When the time to remove the falsework arrives, the collars 13 are removed and the false-work taken down and then the arms of the hanger are cut off at the bottom of the rib 9 as usual.

In Fig. 2, 15 indicates a concrete column, 16 the false-work or form, 17 vertical ribs strengthening the forms, 18 cross bars engaging the outer sides of the ribs and 19 rods extending through the column, false-work, and bars 18 and also through the ribs 17, if desired.

To hold the forms or falsework in proper position, collars 13 are mounted on opposite ends of rod 19 and bear against the cross bars and set screws 14 hold the collars in place.

In this construction after one collar 13 is set at the desired point and so secured by its set screw 14, the other collar 13 is adjusted by means of the collar adjusting

clamp in the same manner that collars 13 of Fig. 1 were adjusted.

From the above description it will be apparent that I have produced a collar adjusting clamp which will perform its function efficiently and which embodies the desirable features of simplicity, strength, durability and cheapness of construction.

I claim:

- 10 1. In a mold clamping device, a tie-rod, two clamping collars mounted on said rod, each collar having means for being secured tightly to said rod, one of the collars being longitudinally adjustable on said rod, and
- 15 a tightening device adapted for longitudinal expansion and contraction and for longitudinal adjustment on and having means for being releasably locked to said rod, and adapted to engage and longitudinally move

and to be detached from said adjustable 20 clamping collar.

2. In a clamping device, a tie rod, a clamping collar longitudinally adjustable on said rod and having means for being releasably locked thereto, and a tightening device 25 adapted for longitudinal expansion and contraction, and longitudinally adjustable on said rod independently of said clamping collar and adapted for longitudinally moving said collar, and provided with means for 30 being releasably locked to said rod.

In testimony whereof I affix my signature, in the presence of two witnesses.

GEORGE F. NEWTON.
